UNITED STATES PATENT OFFICE

WILLIAM H. LEES, OF LOWELL, MASSACHUSETTS

DECORATIVE FABRIC

Application filed February 12, 1931. Serial No. 515,263.

This invention relates to a lustrous decorative fabric.

The object of the invention is to provide a novel and improved lustrous fabric for general decorative purposes which may be economically made, is strong and durable, and possesses a distinctive and novel appearance, which makes it particularly useful and valuable for general decorative purposes, and particularly in ribbon form for fancy tying.

With this object in view, and such others as may hereinafter appear, the invention consists in the lustrous decorative fabric herein-after described and particularly defined in 15 the claims at the end of this specification.

In the drawing I have illustrated the invention as embodied in a decorative lustrous ribbon.

In general the present invention contemplates a fabric embodying strips of transparent lustrous material preferably comprising the cellulosic material of the type known as regenerated cellulose. In producing the present fabric flat strips of the transparent material either alone or combined with opaque or translucent strips in any of the different colors, including white or black, may and preferably will be utilized as the warp of a woven fabric and the filling may comprise any desired material such as silk, rayon, or cotton thread. The transparent strips preferably comprising strips of regenerated cellulose may also be combined with tinsel in any of the different colors or forms thereof, to produce a variety of novel lustrous fabrics in which the transparency and inherent luster of the regenerated cellulose or equivalent transparent lustrous material supplements the brilliance of the tinsel to set off the same and to produce novel and most attractive and valuable decorative fabrics. The colored transparent strips of regenerated cellulose as well as the colorless transparent strips, will be light-transmitting and light-reflecting and will have greater light-transmitting properties than more highly colored transparent, translucent, or opaque strips of regenerated cellulose or tinsel strips, and when combined as above described, will by 50 their contrasting properties produce an un-

usual and attractive fabric. Also it can be seen that the use of colorless transparent strips with substantially non-transparent strips such as the more highly colored transparent, translucent, or opaque strips of regenerated cellulose or the tinsel strips, will give the same effect.

Referring now to the drawing, which as above stated illustrates the preferred embodiment of the invention, 10 represents a woven fabric of any desired width, herein shown for illustrative purposes as comprising a ribbon or narrow fabric. The fabric 10 is herein shown as made up of warp strands 12 and weft threads 13. The warp strands 12 are herein shown as comprising a plurality of transparent strips 15 of regenerated cellulose or equivalent material and brilliant metallic or colored tinsel strips 16. If desired, the tinsel strips 15 may be omitted and regenerated cellulose alone used, according to the effect desired to be produced. The regenerated cellulose strips 15 with or without the tinsel strips 16 are woven with a weft 13 comprising any suitable filling material, such as for example as a silk, cotton or rayon thread to produce the fabric. It is preferred to weave the weft in and out at a relatively small number of picks to the inch, in order that the weft may be spaced apart, as illustrated in the drawing.

For the production of narrow fabrics utilized as decorative ribbons for general fancy tying purposes, the regenerated cellulose strips may be used in widths approximately one-sixteenth inch, and are preferably woven in the form of flat strips so that the flat regenerated cellulose strips may impart to the fabric a maximum luster and transparent effect. The weaving operation may be performed upon narrow fabric looms of known construction in accordance with the usual practice followed in producing tinsel ribbon.

The regenerated cellulose strips 15 may be colorless so as to impart to the ribbon merely a lustrous effect, or they may themselves be colored, and in the fabric the joints between the sides of adjacent strips of the regenerated cellulose are visible only upon relatively close examination so

that when viewed from a distance the regenerated cellulose appears as a transparent sheet, and when combined with tinsel, and particularly colored tinsel, the transparency of the regenerated cellulose strips imparts the appearance to the fabric of a plurality of the tinsel strips alone, presenting an unusual, distinctive, and pleasing appearance. The regenerated cellulose strips possess a high degree of luster and contribute to the brilliance of the fabric.

While it is preferred to utilize transparent material of the type known as regenerated cellulose, nevertheless viewed in the broader aspects of the invention other transparent lustrous material of an equivalent nature may be used.

While the preferred embodiment of the invention has been herein illustrated and described, it will be understood that the invention may be embodied in other forms within the scope of the following claims.

Having thus described the invention, what is claimed is:—

25 1. A lustrous, decorative fabric comprising as a warp a set of flat, thin, decorative non-transparent strips, and another set of thin, flat strips of transparent regenerated cellulose, said fabric having strips of one set 30 of warp strips interposed between strips of the other set, and having thin, weft threads whereby adjacent warp strips are positioned close together and substantially in the same plane, said weft threads being spaced relatively far apart whereby the surfaces of the portions of said warp strips between said weft threads form individual light-reflecting facets.

40 2. A lustrous, decorative fabric comprising as a warp a set of flat, thin tinsel strips and a set of flat, thin strips of transparent, regenerated cellulose, said fabric having strips of one set of warp strips interposed between strips of the other set, and having 45 thin, weft threads whereby adjacent warp strips are positioned close together and substantially in the same plane, said weft threads being spaced relatively far apart whereby 50 the surfaces of the portions of said warp strips between said weft threads form individual light-reflecting facets.

55 3. A lustrous, decorative fabric comprising as a warp a plurality of sets of thin, flat, light-reflecting strips, one of said sets being composed of thin, flat strips of non-transparent regenerated cellulose and another set composed of transparent regenerated cellulose, said fabric having strips of one set 60 interposed between strips of the other set and having thin, weft threads whereby adjacent warp strips are positioned close together and substantially in the same plane, said weft threads being spaced relatively far apart 65 whereby the surfaces of the portions of said

warp strips between said weft threads form individual light-reflecting facets.

In testimony whereof I have signed my name to this specification.
